L. GRAU

SIGNAL CANE

Filed April 2, 1925

Fig. 1.

UNITED STATES PATENT OFFICE.

LOUIS GRAU, OF BROOKLYN, NEW YORK.

SIGNAL CANE.

Application filed April 2, 1925. Serial No. 20,256.

To all whom it may concern:

Be it known that I, LOUIS GRAU, a citizen of the United States, and a resident of the city of New York, Bensonhurst, borough of Brooklyn, in the county of Kings and State of New York, have invented a new and Improved Signal Cane, of which the following is a full, clear, and exact description.

This invention relates to signal devices for canes and the like and has for an object to provide an improved construction wherein the usual cane structure is presented and at the same time means are provided for producing a light at or near one end of the cane.

Another object of the invention is to provide a signal cane wherein means are provided for presenting an electric lamp adjacent the lower end of the cane with means associated therewith for supplying the lamp with current and presenting a switch mechanism near the grip of the cane so that the lamp may be lighted while the hand of the operator holds the grip of the cane.

25 In the accompanying drawing—

Figure 1 is a side view of a cane disclosing an embodiment of the invention.

Figure 2 is an enlarged fragmentary sectional view through the cane shown in Figure 1, certain parts being broken away in order to better illustrate the construction.

Referring to the accompanying drawing by numerals, 1 indicates the body of the cane which is provided with the usual grip 2 and the usual ferrule 3. The body 1 is preferably divided at 4 so that the upper section 5 is integral with the grip 2 while the lower section forms in effect the body 1. In order to produce a pleasing appearance at the point of division 4, ornamental ferrules or bands 6 and 7 are mounted on the respective sections 5 and 5'. As these rings are in contact when the cane is in use, the same appear to be merely ornamental rings rather than ferrules. The section 5 carries a metallic rod 8 which is secured in place in any desired manner, as for instance, by friction and adhesive. The rod 8 is formed with an enlargement 9 having a threaded section 10 adapted to be screwed into section 5' of body 1 whereby the sections 5 and 5' are firmly connected together.

From Figure 2 it will also be noted that an extension 11 projects from the threaded portion 10 and presses against the resilient contact 12 of battery 13. The resilient con-

tact 14 of battery 15 engages the lower end of battery 13 while the lower end of battery 15 is in contact with a ring 16 connected to a conductor 17, which conductor extends through a suitable groove 18 in the body 1 and at the lower end is connected to a contact plate 19 against which the central contact 20 of lamp 21 presses when the lamp is in operative position. It will be understood that the contact spring 14 engages the casing of the battery 13 as said casing extends across the bottom and the same is true of ring 16 in order that a proper circuit or connection of the batteries may be provided so that the full voltage of each battery is secured. The shell 22 of lamp 21 is in engagement with the socket 23 when the lamp 21 is in operative position, said shell having a conductor 24 connected thereto, which conductor is fitted into a groove 25 and extends upwardly to the ferrule 7 to which it is secured. The groove 18 is provided with a suitable filling member 26 which may be a piece of wood or other filling member to hold the wire 18 in place and to provide a proper surface for the cane so that it may be finished evenly throughout. The same is true of the groove 25 which may be in line with groove 18 or offset therefrom. In the drawing, a small strip 27 of wood or other suitable material is placed in the groove on top of the conductor 24 so as to cover the same and provide a proper surface agreeing in color and appearance with the rest of the body 1. A spring 28 is soldered or otherwise secured to the ferrule 6 and carries a contact member 29 at the free end as well as a push button 30, which push button extends through a suitable aperture 31 in section 5. The contact 29 is normally spaced from the rod 8 and the spring 28 is so positioned that when the button 30 is depressed, contact 29 will engage rod 8 and close the circuit at this point which is the only point where the circuit is open. When the contact 29 is in engagement with the rod 8, current will flow from the batteries through wire 18 to lamp 21 and from thence through wire 24 to ferrule 7 and from ferrule 7 through ferrule 6, spring 28, contact 29, rod 8, enlarged portion 9, threaded section 10 and extension 11 back to the batteries.

From Figure 1 it will be noted that the push button 30 is positioned very near the grip 2 while the lamp 21 is positioned near the lower end of the cane.

In operation, the person using the cane may readily press the button 30 without releasing the grip 2 and may also move the lower end of the cane to any desired point 5 which it is desired to illuminate. It will thus be seen that the cane may be used for illuminating dark places and also may be used to signal from an automobile or from any other place either by waving or by flashing on and off as desired.

What I claim is:

1. A signal cane, comprising a cane body provided with a grip and divided into two parts near the grip, a member secured to 15 one part formed with a threaded portion adapted to be screwed into the other part for firmly connecting said parts together, said parts at the point of contact being provided with a pair of metallic ferrules, a 20 button operated contact co-acting with said member, said contact being electrically connected with one of said ferrules, a lamp adjacent the end of the cane opposite the grip, a conductor connected with the other 25 of said ferrules and with one side of said

lamp and a battery arranged in said body, a conductor connecting one side of said battery with the other side of said lamp, and means for connecting said battery with said member having the threaded portion whereby when said button is operated for actuating said contact the circuit of said lamp will be closed. 30

2. A signal cane, comprising a cane body divided into two parts, a metallic ferrule 35 connected with each of said parts at the point of juncture, a screw member connected with one of said parts and adapted to be screwed into the other part for locking the parts together, an electric lamp arranged 40 adjacent one end of the cane, a push button arranged at the opposite end of the cane, and means forming a circuit for said lamp, said means including a source of current, said ferrules, and extension, from said 45 threaded member and the metallic contact carried by said button positioned to be brought into engagement with said extension when the button is depressed.

LOUIS GRAU.
